UNITED STATES PATENT OFFICE.

CHARLES O. HEON, OF PORTAGE, WISCONSIN, ASSIGNOR TO HEON REMINDER CLOCK COMPANY, INC., OF JANEVILLE, WISCONSIN, A CORPORATION OF WISCONSIN.

PROGRAM-CLOCK.

1,136,602.

Specification of Letters Patent. Patented Apr. 20, 1915.

Application filed January 28, 1913. Serial No. 744,711.

To all whom it may concern:

Be it known that I, CHARLES O. HEON, citizen of the United States, residing at Portage, in the county of Columbia and

5 State of Wisconsin, have invented certain new and useful Improvements in Program-Clocks, of which the following is a specification.

My invention relates to new and useful 10 improvements in clocks and more particularly to time clocks or time reminders or as they are more commonly called program clocks and the object of my invention is to provide a clock so arranged that it may be 15 adjusted to signal an operator at certain predetermined times for denoting certain things to be done at those times.

A further object of my invention is to so 20 arrange the mechanism for accomplishing this that the device will be able to be set to give a signal not only upon the hours, half hours and quarter hours as is now the custom, but at five minute intervals, that is on the hour, 5 minutes past the hour, 10 minutes 25 past the hour or 15 minutes past the hour, as desired.

A further object of my invention is to accomplish this without the use of the detachable plugs now commonly employed in 30 closing the circuit in clocks of this type. And a still further object of my invention is to provide a plurality of rotatable contact members, each of which may be turned to any one of a number of positions in such a 35 manner that each member may be employed as a circuit closer to give the signal at any one of a number of times. For instance, the contact member which would be normally employed in closing the circuit to give a 40 signal at 1 o'clock will be so constructed that by proper adjustment it may be employed to close the circuit to give the signal at either 5 minutes of one, one or 5 minutes past 1, as preferred.

45 With these and other objects in view, my invention will be more fully described, illustrated in the accompanying drawing, and then specifically pointed out in the claims which are attached to and form a part of 50 this application.

In the drawing: Figure 1 is an elevational view of the clock time showing my invention applied thereto; Fig. 2 is a fragmentary detail elevation, showing one of the rota-

table contacts and the spring by means of 55 which it is held in adjusted position, the various phases of adjustment of the contact being shown in dotted lines.

Corresponding and like parts are referred to in the following description and indicated in all the views of the drawing by the same reference characters.

For the sake of clearness I have illustrated my invention as employed in connection with a conventional clock, a portion of 65 the casing of which is shown at 20, this clock having a dial 21 of the common type, a minute hand 22 and an hour hand 23. Attached to the arbor of the hour hand, is a fiber disk 24 and a steel spring 25 bears 70 by one end against this disk to hold the hour hand in train with the clock movement at all times, the opposite end of the spring being secured to an adjacent part of the clock movement by a screw 26. As will be 75 later explained, the hour hand 23 forms the movable contact member of the signaling circuit and is therefore subject to slight strain when the circuit is closed and it is for this reason that I have provided the 80 fiber disk and spring 25. Otherwise the clock is of conventional type.

Secured to the clock casing and encircling the dial of the clock, is a contact carrying ring 27 formed of any suitable current conducting material, preferably brass. A plurality of pairs of spaced eyes 28 are carried by this ring, the eyes of each pair being in radial alinement with each other with respect to the clock dial and each pair of eyes 90 being spaced an equal distance from the eyes of adjacent pairs. One pair of eyes is positioned in alinement with each of the hour divisions of the dial and three other pairs of eyes are equally spaced between the 95 pairs of eyes of adjacent hour divisions in such a manner that on the hour, half hour and quarter hour, the hour hand of the clock will always be pointing directly toward one pair of eyes.

100 Rotatably mounted in each pair of alined eyes are contact members, indicated as a whole by the numeral 29. These members are formed of current conducting metal, preferably brass and are provided at their 105 inner ends with laterally directed contact terminals 30 each of which is provided at its free end with a slightly overhanging

shoulder 31. The opposite ends of the contact members 29 are provided with laterally bent operating arms 32 by means of which the members may be turned to adjusted position and the members are normally held in position by leaf springs 33. As best shown in Fig. 1 of the drawings, these springs 33 are secured by their intermediate portions to the contact ring 27 by screws or other suitable fastening devices 34 in such a manner that the free ends of the springs bear over the intermediate portions of adjacent contact members 29, one spring being necessary for every two contact members.

15 Those portions of the rotary contact members 29 against which the ends of the springs 33 bear are provided with a plurality of longitudinally extending flattened faces 35 so arranged that each contact member 29 20 may be turned in either direction to bring its terminal 30 into a plane parallel with the clock dial or into a plane at right angles to the clock dial. Furthermore, the faces are so arranged that the member 29 may be 25 turned in either direction to bring its contact terminal into a plane at 45 degrees to the clock dial and when turned in any one of the above positions, the co-acting spring will bear flatly against one of its angular 30 faces to hold the same against turning.

35 The hour hand 23 carries an extremely flexible resilient contact 36 which extends beyond the free end of the hand and in alignment with the hand and the free end 30 of which is flattened or otherwise shaped to engage against the contact terminals 30 of whatever contact members may be adjusted to raise the terminals from a plane parallel to the plane of the clock dial.

40 The contact ring 27 is provided with a binding post 37 while some portion of the clock movement is provided with a similar binding post 38. A wire 39 leads from the binding post 38 to a battery or other suitable source of energy 40, while a wire 41 leads from the binding post 37 to one binding post of a bell or other electric signaling device 42. A wire 43 connects the other binding post or signaling device 42 with the 45 free pole of the battery 40. Inasmuch as the wire 39 and hour hand 23 are both in electrical connection with the movement of the clock, it will be apparent that whenever the contact member 36 of the hour hand 50 engages one of the rotatable contact members 29, the circuit through the bell 42 will be closed and the signal sounded.

55 In order to protect the rotatable contact members from displacement and also from dust and dirt, I preferably provide an annular casing 44 which fits over the contact ring 27 and the intermediate portions of the contact members 29 and which preferably carries the glass face of the clock. By 60 this means, the inner or contact terminals

of the members 29 are protected from dust, dirt, grease or other foreign matter and a good electrical contact is therefore insured.

70 The rotatable contact member located adjacent each hour division of the clock dial is mounted in such a manner that when its contact terminal extends at right angles to the clock dial, it will be engaged by the hour hand of the clock exactly on the hour, while if it is turned to one side to extend at an angle of 45 degrees of the dial, it will be engaged by the hour hand 5 minutes before the hour and if turned in the opposite direction to extend at an angle of 45 degrees from the hour hand, it will be engaged 5 75 minutes after the hour. It will therefore be apparent that the contact member at each hour division of the clock may be adjusted to give the signal either at the hour or 5 minutes before or after the hour, as desired. 80 In like manner the contact members arranged to give the signal at the half hour and quarter hour positions of the hour hand may be adjusted to give the signal 5 minutes 85 earlier or later, as preferred.

90 Under normal conditions, all of the contact members occupy the position shown in Fig. 1 of the drawings in which the contact terminals of the members 29 lie parallel with the dial face of the clock in such a manner 95 that the contact 36 carried by the hour hand will pass over the same without touching them and consequently without giving any signal. The projecting ends of the contact members 29 having lateral operating arms 32 provide a ready means for swinging the contact members to adjust them for any desired setting of the clock signal.

100 From the foregoing description it will be apparent that I have so arranged my memorandum clock as to absolutely do away with all detachable plugs now in use and in such a manner that each adjustable contact member is made to do the work formerly done by three contact members. Furthermore, 110 the springs holding the contact members in adjusted position are so arranged that each spring serves as a lock for two contact members, thus greatly decreasing the expense of manufacture of the signaling device.

115 It will of course be understood however, that I do not wish to limit myself to the specific details of construction illustrated and described as various changes may at any time be made without in the slightest 120 degree departing from the spirit of my invention.

Having described my invention, what is claimed as new is:

1. A signal device to coöperate with an 125 indicator having a hand, including a plurality of electrically connected spaced contacts movable into and out of operative position for engagement by the hand during movement of the latter and each mov- 130

able into position to be engaged by the hand at different predetermined positions thereof, and means for determining when they have reached any one of such predetermined positions.

2. A signal device to coöperate with an indicator having a hand, including a contact ring, and a plurality of spaced contacts carried by the ring and movable into and out of position to be engaged by the hand during movement of the latter, each of the contacts including a radially extending body member mounted to turn about its longitudinal axis and provided at its inner end with a laterally directed contact terminal.

3. A signal device to coöperate with an indicator having a hand, including a contact ring, a plurality of contact members positioned in spaced relation about the ring and extending radially with respect thereto, the inner ends of said contact members having laterally bent contact forming terminals, and the outer ends of said contact members having laterally bent operating arms, said contact members being mounted for turning movement about their longitudinal axes.

4. A signal device adapted for attachment to an indicator having a hand, including a contact ring positioned in the path of movement of the hand, a plurality of eyes arranged in radially alined pairs upon the ring, each pair of eyes being spaced from adjacent pairs, a contact member revolvably mounted in each pair of eyes and provided at its inner end with a contact terminal for engagement with the indicator hand and intermediate its length with angularly formed faces, and means for holding said contact members in adjusted position.

5. A signal device adapted to coöperate with an indicator having a movable hand, including a contact ring, a plurality of eyes arranged in radially alined pairs upon the ring, each pair of eyes being spaced from the adjacent pair, a contact member rotatably mounted in each pair of eyes and provided at its inner end with a contact terminal for engagement with the indicator hand and intermediate its length with angularly formed faces, and leaf springs secured intermediate their length between adjacent contact members and bearing by their free ends upon the angular faces of such contact members to hold them in adjusted position.

6. A signal device including a contact carrying member adapted to be included in circuit with the hand of an indicator, a plurality of contacts carried by such member with laterally directed terminals movable into and out of the path of the hand by rotation of the contacts about their longitudinal axes, and leaf springs secured to the contact carrying member and engaging the intermediate portions of the contacts to frictionally hold them against turning.

7. A time reminder including a clock having an hour hand, a concentrically located contact ring, and a plurality of contact members in engagement therewith with their longitudinal axes extending radially of the ring, each being movable into and out of position to be engaged by the hand through rotation about its longitudinal axis.

In testimony whereof I affix my signature in presence of two witnesses.
